(57) **CLAIM**

The ornamental design for a charging pile, as shown and described.

DESCRIPTION

FIG. 1 is a front, top, right side perspective view of a charging pile showing my design.

FIG. 2 is a rear, bottom, left side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view thereof, taken from portion 9 in FIG. 1.

FIG. 10 is a front, top, right side perspective view of the charging pile in use with charging plugs and cables; and, FIG. 11 is a rear, bottom, left side perspective view of the charging pile in use with charging plugs and cables.

The broken lines in the drawings illustrate portions of the charging pile that form no part of the claimed design. The broken lines showing charging plugs and cables in FIGS. 10-11 depict environment and form no part of the claimed design. The dot-dash broken lines in FIG. 1 and FIG. 9, the number "9" in FIG. 1 are included to show a partially enlarged view only and form no part of the claimed design.
